UNITED STATES PATENT OFFICE.

BLUFORD W. BROCKETT, OF CLEVELAND, AND DANA H. BENJAMIN, OF CLEVELAND HEIGHTS, OHIO.

PRESSING-MACHINE.

1,383,520.

Specification of Letters Patent.

Patented July 5, 1921.

Application filed January 13, 1917. Serial No. 142,277.

To all whom it may concern:

Be it known that we, BLUFORD W. BROCKETT and DANA H. BENJAMIN, citizens of the United States, residing at Cleveland and Cleveland Heights, respectively, in the county of Cuyahoga and State of Ohio, have invented certain new and useful Improvements in Pressing-Machines, of which the following is a specification.

10 This invention relates to pressing machines, such as are used for pressing garments or fabrics of any kind.

15 The object of the invention is to provide a pressing machine embodying improved means for applying steam to the work for moistening it and for raising its nap, and also a machine which enables the operator to pat the work after pressing without resorting to the use of a paddle or other special 20 implement. A further object of the invention is to provide a machine which evenly distributes the steam across the work and conserves steam, and which is of simple construction and convenient to operate.

25 Further objects of the invention are in part obvious and in part will appear more in detail hereinafter.

The invention comprises the pressing machine hereinafter described and claimed.

30 In the drawings, Figure 1 is an end elevation, showing the press open; Fig. 2 is a detail sectional elevation on a larger scale, on the line 2—2, Fig. 1; Fig. 3 is a cross section on the line 3—3, Fig. 4; Fig. 4 is a plan 35 view of the supplemental frame, the pressing plate and fabric diaphragm being omitted; Fig. 5 is a plan view, broken out to show the supplemental frame; and Fig. 6 is a front view partly in section.

40 The machine shown in the drawings comprises a suitable frame 1 near the front of which is a column 2 supporting the lower pressing member 3, which is of common form, being provided with a hollow heating

45 chamber 4 connected to a suitable source of steam supply, the upper wall 5 of said chamber separating it from a combined heating and vacuum chamber 6 above which is the perforated plate 7 covered with padding 8.

50 Steam may be admitted to said chamber 6 and discharged through the perforated plate and padding and distributed to a garment or other article lying on the padding by opening a valve 9 controlling the flow 55 of steam through passages 10 from chamber

4 to chamber 6. Said valve may be of any suitable form, for example as shown in the patent of William E. Andree for garment press, Patent No. 1,368,684, of Feb. 15, 1921, filed June 7, 1916. As it forms no part of the present invention no further description of said valve is necessary than to state that it is operated by raising or lowering a rod 11 operated by a foot treadle 12.

60 Chamber 6 may also communicate with a passage 13 connected by pipe 14 to a suitable source of vacuum or suction, such as a constantly operating fan or air pump 14, the passage being controlled by a valve 15 operated by rod 16, as in the Andree application already referred to. By opening valve 15 any steam or moisture in, on or near the padding or a garment thereon is withdrawn through chamber 6 and pipe 14, thereby quickly drying the work, keeping 75 the pad dry and preventing discharge of steam into the room.

70 At the back of the frame is a column 17 forming a support for the lever 18, one arm of which carries the upper pressing member 80 or head 19 balanced by a weight 20 on the other arm. The head may be advanced or depressed into pressing relation with the lower pressing member by any suitable operating mechanism, such as the two toggle 85 links 21 connected by a link 22 to a lever 23 pivoted in the frame and connected by a link 24 to a foot treadle 25. The head is normally held elevated by the usual tension spring or springs 26.

90 The head is of substantially the same form as the lower pressing member, being provided with a heating chamber through which steam is circulated from the supply pipe 27 through pipe 28 to said chamber 95 thence by way of pipe 29 to the outlet pipe 30. No padding need be used on the upper pressing member, whose lower face can be a plain imperforate metal surface.

100 Between the upper and lower pressing members is located a supplemental frame which serves two purposes, first to supply steam, when required, to the garment or other work, and second, as a means where-with to pat or tap the garment to release 105 the steam therefrom and improve the finish. This frame comprises a peripherally extending tubular member 31 bent to conform to the shape of the pressing members and connected by tubular arms 32 to short pipe sec- 110

2

tions 33 in the steam supply pipe 28 and discharge pipe 29 of the upper pressing member. Swivel joints 34 permit either said frame or the upper pressing member to tilt 5 or turn independently of the other on the axis of pipes 28, 29. In the frame member 31 and its connected pipe members are suitably located plugs 35 which cut off or deaden part of the frame but allow steam to flow 10 through one hollow arm 32 in the direction of the arrows, Fig. 4, to a live section 36 of the frame, which section is provided with a series of spaced apertures 37. The upper face of the supplemental frame is completely 15 covered by a continuous press plate 38, which may be a comparatively thin metal plate riveted or otherwise secured to the pipe frame. Below said press plate is a flexible diaphragm consisting of a cloth or fabric 20 sheet 39 which may be removably held in place by a spring ring or frame 40 snapped into place as shown in Fig. 3. The space or cavity 41 between the press plate and diaphragm communicates with the ports or openings 25 37 of the live steam pipe and steam may be supplied to said space by opening the normally closed spring pressed valve 42 in the supply pipe. This valve is operated by pulling over a lever 43 connected by a wire or 30 cable 44 to a bell crank lever 45 engaging the valve stem.

The supplemental frame may be suitably counterbalanced so as to be more easily moved by the operator, either by a suitable 35 spring or by the counterweight 45 on the arm 47 connected to said frame. This counterweight, or the spring, may be adjusted to hold the supplemental frame stationary in any position in which it is placed, but preferably slightly overbalances the frame so 40 that normally it will always rise and follow the upper pressing member when the latter is elevated.

In use of the apparatus the garment or 45 fabric to be pressed is arranged on the lower pressing member in the usual manner. Steam may then be applied to the garment or other work either by discharging it from the chamber 6 of the lower pressing member 50 or by means of the supplemental frame. The steaming chamber in the lower pressing member is used in the ordinary manner which need not be described in detail. In utilizing the supplemental frame for steaming, 55 said frame alone may be pulled down upon or near the work by grasping the dead pipe section with the hand, or the upper pressing member may be moved downward, thereby carrying the supplemental frame with it, as 60 will be readily understood. When the supplemental frame is close to the garment the valve operating handle 43 is moved over to the left, thereby opening valve 42 causing a 65 flow of steam from the supply pipe to the live pipe section of the supplemental frame

and thence into the space or cavity 41 beneath the press plate. Steam fills this space, puffs out the fabric diaphragm into bag form, depending upon how tightly it is stretched, and then is discharged through 70 the diaphragm and evenly distributed over the work lying beneath the same. Each operation of the valve controlling handle produces a quick puff or flash of steam. The upper pressing member 75 is then brought down into close pressing relation with the work and the final heavy pressure applied to said pressing member in the usual manner. The press plate 38 is of thin metal so that the heat of the upper 80 pressing member is quickly transferred through said plate to the garment to effectively press the same. The pressing members are then released and the steam valve 42 again opened to apply a quick flash of 85 steam to the work for raising its nap. If desired the operator can then take hold of the supplemental frame and move it quickly downward one or more times into contact with the work to pat the same and raise the 90 steam therefrom, but without the necessity of resorting to a special paddle or tool for this purpose. The steam and moisture on the work and in, on or near the padding of the lower pressing member may be then 95 withdrawn through the lower pressing member by suction, as already referred to.

When the upper pressing member is elevated the supplemental frame will also rise to follow it. The machine can consequently 100 be operated in exactly the same manner as ordinary machines not equipped with a supplemental frame, and the operator can in effect forget that the supplemental frame is present. However, the supplemental frame 105 can always be resorted to, and usually is, for the purpose of applying steam to the work or for patting the same to cause the steam to rise therefrom.

What we claim is:—

110 1. A pressing machine, comprising a lower pressing member for supporting the garment, an upper pressing member coöperating therewith, means separate from said pressing members and lying between the 115 same for discharging steam upon an article upon the lower pressing member, and steam supply means therefor.

115 2. A pressing machine, comprising relatively movable upper and lower pressing members, a separate and movable steaming device adapted to be adjusted to a position over and adjacent an article upon the lower member and from which steam may be discharged thereon, and means for supplying 120 steam thereto.

125 3. A pressing machine comprising relatively movable pressing members, a separate hollow pervious device adapted to be moved to a position over and adjacent an article 130

- between said members, and means for supplying steam to the chamber in said device.
4. A pressing machine comprising relatively movable pressing members, and a separate hollow device located between said members and movable toward and from one thereof and connected to a source of steam supply.
5. A pressing machine comprising relatively movable pressing members, and a separate hollow device located between said members and movable toward and from one thereof and connected to a source of steam supply, said device having a pervious wall through which steam can pass.
6. A pressing machine comprising relatively movable pressing members, and a separate hollow device located between said members and movable toward and from one thereof and connected to a source of steam supply, said device having a pervious wall through which steam can pass and an impervious wall.
7. A pressing machine, comprising a stationary lower pressing member, an upper pressing member movable relatively thereto, a separate hollow device lying between said members and having a pervious lower wall, and means for supplying steam thereto.
8. A pressing machine, comprising relatively movable pressing members, a separate frame interposed between said members, an upper impervious press plate carried by said frame, a lower foraminous member also carried by said frame, and means for supplying steam to the space between said plate and the foraminous member.
9. A pressing machine, comprising relatively movable pressing members, a separate frame movable relatively to one of said members, an impervious press plate carried thereby and coextensive with the pressing area of said members, and a lower foraminous member carried by said frame beneath said plate.
10. A pressing machine, comprising a frame, a stationary pressing member, a movable pressing member hinged to said frame, a supplemental frame hinged to said frame on the same axis as the movable pressing member and having a hollow portion lying
- between said members, and means for supplying steam thereto.
11. A pressing machine, comprising a frame, a stationary pressing member, a movable pressing member hinged to said frame, a supplemental frame hinged to said frame on the same axis as the movable pressing member and having a continuous press plate lying between said members and a pervious diaphragm beneath the same, and means for supplying steam to the space between said plate and diaphragm.
12. In a press, a buck, a head, means for bringing the same into pressing position, and steaming mechanism comprising an envelop lying beneath the head and movable bodily with respect thereto, and means for projecting steam into said envelop.
13. In a press, a buck, a head, a support therefor, means for bringing the head into pressing relation with the buck, and steaming mechanism carried by said support independently of said head, and comprising an envelop co-extensive with the pressing area of the buck and head and adapted for engagement with the ironing surface of the head, and means for projecting steam into said envelop.
14. In a press, a buck, a head, a support therefor, means for bringing the head into pressing relation with the buck, and steaming mechanism carried by said support independently of said head, and movable relative to said support, and comprising an envelop co-extensive with the pressing area of the buck and head and adapted for engagement with the ironing surface of the head, and means for projecting steam into said envelop.
15. A pressing machine comprising relatively movable pressing members, a hollow device movable with respect to each of said members and adapted to be moved to a position over and adjacent an article between said members, and means for supplying steam to the chamber in said device.

In testimony whereof we affix our signatures.

BLUFORD W. BROCKETT.
DANA H. BENJAMIN.
